UNITED STATES PATENT OFFICE.

BURT E. TAYLOR, OF WAUSEON, OHIO, ASSIGNOR TO C. D. CHEWNING, OF RANDOLPH, NEW YORK.

FILLING-MACHINE.

No. 874,639.

Specification of Letters Patent.

Patented Dec. 24, 1907.

Application filed March 7, 1907. Serial No. 361,185.

To all whom it may concern:

Be it known that I, BURT E. TAYLOR, a citizen of the United States, and a resident of Wauseon, in the county of Fulton and State of Ohio, have invented a certain new and useful Filling-Machine; and I do hereby declare the following to be a full, clear, and exact description of the invention, such as will enable others skilled in the art to which it applies to make and use the same, reference being had to the accompanying drawings, and to the figures of reference marked thereon, which form a part of this specification.

My invention relates to filling-machines, and has reference more particularly to machines of this class employed for the packaging of liquids, but the novel features thereof appropriate for use in other connection are not restricted to such use.

In the use of machines of this class considerable difficulty has been experienced in the provision of means for positively feeding the cans to the machine in a uniform and easy manner, so that the several can-receiving parts of the machine successively receive a can in proper vertical position to be filled.

One of the objects of my invention is to obviate the difficulties incident to the feed mechanisms heretofore employed, by the provision of simple and efficient means for quietly and successively delivering the cans to the machine in proper vertical position to be filled, as hereinafter fully described.

A further object of my invention is the provision in a machine of this class of can-carrying pockets, which have parts thereof adjustable to enable them to be easily and readily changed to suit different sizes of cans to be fed thereto without necessitating the entire removal of the pockets and substitution of others of the proper size therefor.

Further objects, as well as the operation, construction and arrangement of the parts of the invention will be apparent by reference to the following specification and the accompanying drawings illustrating the same, in which,

Figure 1 is a side elevation of the machine embodying the features of my invention, with the feed mechanism removed and only a portion of the filling parts shown. Fig. 2 is a plan view of the feed mechanism and an associated portion of the can-carrying table. Fig. 3 is a vertical elevation of the feed mechanism with the supporting table and ro-

60
tary can-carrying table in section on the dotted line x x in Fig. 2. Figs. 4 and 5 are plan and sectional views of one of the adjustable can-carrying pockets, and Fig. 6 is an enlarged vertical section of a portion of the liquid tank of the machine and an associated filling nozzle, with the operative parts of the latter shown in extreme open position and a can partially lowered from contact with such nozzle.

65
Referring to the drawings, 1 designates the rotary can-carrying table of a filling-machine embodying the features of my invention; 2 the superimposed liquid tank, which is fixed to a vertical shaft 3 with the table 1, said shaft having its lower end rotatably mounted in a standard 4; 5 the filling valves or nozzles carried by the tank; and 6 the platform, which is located in contiguous position to one side of the rotary table 1 and carries the can- 70 feeding mechanism.

75
The rotary table 1 has circularly arranged adjacent its outer edge a plurality of equidistant can-carrying pockets 7, corresponding in number to the number of filling-nozzles 5 of the tank and each falling directly under one of said nozzles. These pockets are fixed to the upper ends of short shafts or stems 8, which are mounted for vertical movement within sleeves 9 secured to the 80 under side of the table 1 and carry idler-rolls 10 at their lower ends. The rolls 10 travel on a stationary track 11 beneath the table, said track having its surface fashioned to impart the requisite vertical movements to the 85 pockets and cans 12 carried thereby, as is hereinafter more fully described. The vertical walls of each pocket are composed of the two oppositely positioned bars 13, which are pivoted adjacent the outer corners of the 90 plates forming the bases of the pockets, as at 14, and have their inner ends converging and each secured to its base in proper position to suit the size of cans being filled, due to a screw 15 or other suitable means engaging 95 one of a series of apertures 16 in the base. With this construction of pocket it is apparent that a widened mouth is provided and that the rear or inner portion thereof may be contracted or widened as the size of can being used may require, it being understood, of course, that the adjustment must be such that each can when in position, or at the rear of the pocket, will be centered under the associated filling nozzle. The pockets are pre- 100

105
110

- vented from having a turning movement relative to the table 1 by studs 17, which are carried by the pockets and loosely projected through apertures 18 in the table.
- 5 The feed mechanism of my machine comprises a feed-wheel 19, which is mounted above the platform 6 on a short vertical shaft 20 projecting through a suitable bearing therein. This wheel is provided with a 10 plurality of peripheral can-engaging pockets or notches 21, which are intended to sweep over the platform and the contiguous edge of the table 1 when the shaft 20 is rotated. The wheel 19 is driven at a uniform speed with 15 the table 1 due to the toothed wheel 22 being carried by the shaft 20 beneath the platform and engaging the flanged upper ends of the sleeves 9, as shown in Fig. 3 and by dotted lines in Fig. 2. The peripheral notches 21 of 20 the feed wheel are so arranged that when revolved with the table 1 they register with the pockets 7 thereof so that the cans fed to the feed-wheel are delivered thereby to the successive pockets 7 of the table.
- 25 The cans 12 are fed to the feed-wheel from an elevated plane, preferably the floor above, through a vertically disposed trough or magazine 23, which has its lower end terminating in contiguous position to the feed-wheel and 30 curved, as shown, to present an inclined surface thereto. The cans are fed to the upper end of the trough in reclining or horizontal position and maintain this position until they reach the curved portion of the trough, which 35 is so formed as to deliver the cans to the feed-wheel in vertical or upright position, as shown. This feature of my feed is quite an important one as it enables the cans to be fed to the feed-wheel by gravity and at the same 40 time eliminates the noise and jar incident to the forms of vertical feeds in which the cans are passed through the feed magazine in vertical position and dropped in such position upon the machine. The cans are delivered 45 to the pockets of the feed-wheel in substantially a plane with its axis and a curved plate 24 is shown as extending from the lower end of the trough in the arc of movement of the pockets or notches 21 of the feed-wheel and 50 upon which the cans are actuated to slide by said feed-wheel prior to moving upon the surface of the platform 6, which latter is in the plane of the upper surfaces of the bases of the can-receiving pockets 7 of the rotary table.
- 55 A curved guide-rail 25 surrounds the delivery side of the feed-wheel, extending from the delivery end of the trough to over the edge of the table 1, and prevents the cans leaving the notches of the feed-wheel until in 60 register with a pocket 7 of the table, as shown in Fig. 2. As the cans enter the pockets 7 of the rotary table they are moved to the rear of the same in proper position to center with the associated filling-nozzle 5 by the action of 65 a guide-arm 26, which is pivoted to the plat-

form 6, as at 27, and projects over the edge of the table 1 and extends a desired distance in the direction of rotation thereof, as shown. The outer or free end of this arm is slidably carried by a horizontally-disposed bolt 28, 70 the outer end of which is pivoted to a plate 29, which is adjustably secured to the platform 6 by a hand-screw 30. A coiled compression spring 31 is carried by said bolt and coacts with the arm 26 to cause it to have 75 yielding contact with the outer sides of the cans.

The shaft 3 carrying the table 1 and tank 2 has rotation communicated thereto from a drive-shaft 46, which is journaled in suitable 80 bearings and carries at its outer end a belt pulley 47 and at its inner end a bevel-gear 48 for meshing with a bevel-gear 49 on the shaft 3.

It will be apparent from the foregoing that 85 as the table 1 and tank 2 revolve the feed-wheel 19 delivers an empty can 12 from the feed-trough 25, which is constantly filled during a running of the machine, to each can-carrying pocket 7 of the table as it passes 90 such wheel, and while the idler roll 10 of the pocket is traveling on the lower plane 11^b of the track 11, and that when a can has been centered in its pocket relative to the associated filling-nozzle 5 by the action of the 95 spring-pressed guide-arm 26, the roll 10 travels up an incline 11^c of the track 11 to effect an elevation of the pocket and its can in position for the latter to be filled.

I wish it to be understood that I do not 100 desire to be limited to the exact details of construction shown and described, for obvious modifications will occur to a person skilled in the art.

Having thus described my invention, what 105 I claim as new and desire to secure by Letters Patent, is—

1. In a filling-machine, the combination with a rotary element having a circular series of can-carrying pockets, of mechanism 110 for successively feeding cans to the pockets as the element revolves, and an adjustable yieldingly mounted member for centering the cans when fed to the pockets.

2. In a filling-machine, the combination 115 with a rotary element having a circular series of receptacle-carrying pockets, and the feed-mechanism therefor, of a receptacle centering member pivoted at one end adjacent the feed mechanism, and adjustable 120 means for causing said member to have yielding contact with the receptacles as they are fed to the pockets.

3. In a filling-machine, a receptacle carrying pocket having side bars forming the 125 pocket walls pivoted at one end to the base and each having its other end adjustably secured thereto, the adjustably secured ends being more contracted than the pivoted ends.

4. In a filling-machine, a can-carrying 130

5 pocket comprising a base plate and spaced bars forming side walls, the forward ends of the bars being pivoted to the plate to provide a broadened receiving mouth and their rear ends being contracted and adjustably secured to the plate.

10 5. In a filling-machine, a rotary table, a plurality of can-carrying pockets mounted for vertical movement relative to the table, each pocket comprising a stem projected through the table, a base plate carried by the stem above the table, side-bars adjustably secured to the plate, means for preventing a turning of the pocket relative to the table, 15 and means co-operating with the stem to

effect a properly timed vertical movement of the pocket when the table revolves.

6. In a filling-machine, a receptacle-carrying pocket having side walls the outer ends of which are spaced to form a receiving 20 mouth while their inner ends are relatively adjustable to enable the intervening space to be contracted or expanded.

In testimony whereof I have hereunto signed my name to this specification in the 25 presence of two subscribing witnesses.
